UNITED STATES PATENT OFFICE

KONRAD TEUFEL, OF LEVERKUSEN-ON-THE-RHINE, GERMANY, ASSIGNOR TO I. G. FARBENINDUSTRIE AKTIENGESELLSCHAFT, OF FRANKFORT-ON-THE-MAIN, GERMANY, A CORPORATION OF GERMANY

ELECTROLYTIC APPARATUS

Application filed February 11, 1928, Serial No. 253,776, and in Germany February 21, 1927.

The present invention concerns a process for safeguarding the uniform passage of electrolytes through electrolytic cells in the manufacture of metals by electrolysis and 5 consists in arranging for the upward flow of the electrolyte, with respect to all electrodes, the electrolyte leaving both sides of the cells by means of overflows arranged for the purpose; the invention also comprises further improvements as will be hereinafter 10 more fully described.

In the electrolytic preparation of metals by the wet process, such as for example, the production of zinc, particular attention has 15 to be given to the circulation of the electrolyte. When the movement provided for the electrolyte is insufficient, impoverishment of the electrolyte as to its metal contents, for example zinc, takes place on those parts of 20 the cathode which have thus suffered. As a consequence of this the formation of buds or sponges as well as a development of hydrogen result, involving considerable disturbances in the electrolysis.

Ordinarily the electrolyte is introduced at 25 one end of the electrolytic cell and leaves it at the opposite end. This arrangement, however, leaves the electrolyte to make its way at random through the bath the gas bubbles mainly rising from the anodes being 30 supposed to promote the movement of the liquid. It is obvious that by such an arrangement a uniform movement of the electrolyte with respect to all the anodes cannot be produced during its passage through the cell. Consequently there was no lack of proposals 35 for remedying this defect. First, for example, attempts were made to render the movement of the electrolyte uniform by

blowing in air or by stirring with rod shaped 40 stirrers which were moved to and fro between the electrodes. According to another proposal intermediate passages were created alternately between the lower end of the anode and 45 the bottom of the vessel and the upper end of the adjacent cathode and the level of the liquid in such a manner that the electrolyte was forced to flow between the electrodes in an upward and downward direction.

These proposals, however, have never met

with any appreciable technical success. In the first instance, this may be due to inefficiency of action. Further the complexity of the appliances involved in the employment of movable parts frequently promotes an excessive wear and tear of the apparatus, inasmuch as the gas bubbles rising out of the electrolyte and being laden with the acid lye are liable to settle on the joints and links of the movable members and rapidly tend to 55 corrode these parts.

Though the last mentioned proposal, providing intermediate passages enables a uniform movement of the electrolyte to be obtained at the lower and upper ends of the electrodes, it still possesses considerable disadvantages. The application of intermediate passages imposes certain limits in regard to size and form of the anodes and cathodes as well as their respective disposition in the 60 bath; the downward current of the lye is of particular disadvantage since it opposes the current of the rising gas bubbles moving in an upward direction whilst the flowing liquid and gas bubbles should of course mutually 65 assist each other.

The present invention describes a process and an appropriate appliance for the execution of the same whereby all requirements are satisfied.

The process consists in introducing the electrolyte from below into the cells at one or more points, depending on the construction of the baths and withdrawing the electrolyte from the upper level of the bath by 70 causing it to pass over weir-like overflows disposed in the upper part of the two opposite cell walls forming right angles with the plane of the electrodes.

For this purpose these overflows should 75 be arranged at an equal level on both sides of the cell, the latter being advantageously provided with a bag for receiving the sludge. The lower part of the cell for this reason is 80 preferably given a prismatic shape or the shape of a pyramid or cone, leaving sufficient space, however, between the lower ends of the electrode or electrodes and the means for 85 supplying the electrolyte.

The bottoms of the cells can like-wise con- 90

sist of frustums of prisms or pyramids or cones or any one of these bottoms may consist of several similar prismatic or pyramid or cone shaped elements. The bag for the 5 sludge referred to may be constructed in such a manner that the tube or tubes introducing the electrolyte is or are extended somewhat beyond the bottom of the cell or a special bag may be provided as is shown 10 in Figure 2 of the attached drawings.

It is important to leave sufficient space between the lower end of the electrodes and the place at which the electrolyte is introduced so as to insure a uniform distribution 15 of the liquid over the whole section of the cell before it reaches the electrodes. This distribution is promoted by the selection of a suitable angle of inclination of the planes of the prisms or pyramids or of the surface 20 of the cone with respect to the horizontal plane.

The overflows can be constructed in such a manner that each overflow extends on each side across the entire length of the cell walls 25 forming right angles with the plane of the electrodes. However, it is also possible to subdivide them into several overflows, for example in such a manner that an individual overflow is placed adjacent to the edge or 30 rim of each individual cathode or anode. In any case, the construction must be effected in such a manner that each individual cathode surface is with certainty brought into contact along its whole extent with the stream 35 of the electrolyte.

It is essential for ensuring a uniform flow of electrolyte to arrange all overflows at exactly the same level; this can easily be achieved by placing thin glass plates within 40 the bath.

The Figures 1 to 6 of the attached drawings represent modes of constructing an appliance in accordance with my invention which are directly understood based on the 45 above description and without adding further details.

Figures 1 and 2 are longitudinal sections, taken in a parallel direction to the electrodes, of two different embodiments of the invention. In these figures the side walls of the 50 cell are represented by 1, while 2 denotes the bi-laterally tapered bottom of the cell acting as a sludge bag. 3 is a pipe for introducing the electrolyte into the cell which in Fig. 1 55 has an extension represented by 4 into the interior of the cell bottom, while in Fig. 2 a double bottom 8 is provided and pipe 3 enters the lower compartment of the cell somewhat above said bottom. 5 are the electrodes; 6 60 the weir-like overflows and 7 indicate outlets for the electrolyte after the latter has passed over 6.

Figures 3, 4 and 5 are ground plans of various shapes of bottoms 2; 4 designates the 65 pipes for introducing the electrolyte.

Figure 3 represents a prismatic bottom Fig. 4 shows a bottom consisting of two and Fig. 5 a bottom consisting of a single pyramid.

Fig. 6 is a horizontal section through a cell 70 taken at the level of the overflows. In this figure the cathodes are represented by 5a and the anodes by 5b; the other numerals having the same significance as in the figures mentioned above. 75

Accordingly the new appliance neither possesses any movable parts that are subject to excessive wear and tear nor does it require permanent control. It enables a uniform flow of the electrolyte at all points of the electrodes and since the electrolyte flows over all the electrodes only in an upward direction, the current of the electrolyte and the rising gas bubbles mutually assist each other. The gas bubbles increase the movement of the electrolyte and render the same completely uniform. The stream of the electrolyte directed upwardly facilitates on its part the removal of the gas bubbles from the electrodes. 85

This is of particular importance in respect to hydrogen bubbles forming on the cathodes, since if these hydrogen bubbles were to remain adherent to the cathodes inequalities of the deposited metal, for example zinc, would result leading to the formation of buds and 90 sponges and finally to short circuiting coupled with increased development of hydrogen. 95

I claim:

1. Apparatus for carrying out electrolytic processes of the kind described, comprising a trough of acid-proof material having vertical side walls and an at least bi-laterally tapered bottom part, a set of parallel vertical electrodes positioned within said trough but arranged so as not to extend into said bottom part, means for introducing a liquid into the lower part of said bottom part and at least two horizontally extending overflows at an equal level in the upper part of the two opposite side walls of said trough perpendicular to the plane of the electrodes. 100

2. Apparatus for carrying out electrolytic processes of the kind described, comprising a trough of acid-proof material having vertical side walls and an at least bi-laterally tapered bottom part, a set of parallel vertical electrodes positioned within said trough but arranged so as not to extend into said bottom part, at least one supply pipe inserted in the proximity of the lowest point of said bottom part and extending into the interior of said bottom part, and at least two horizontally extending overflows at an equal level in the upper part of the two opposite side walls of said trough perpendicular to the plane of the electrodes. 115

In testimony whereof I have hereunto set my hand.

KONRAD TEUFEL.
